(57) **CLAIM**

The ornamental design for a drinking cup with a lid, as shown and described.

DESCRIPTION

FIG. 1 is a top and front perspective view of a drinking cup with a lid, showing our new design.

FIG. 2 is a top and left side perspective view of the drinking cup with a lid of FIG. 1.

FIG. 3 is a top and right side perspective view of the drinking cup with a lid of FIG. 1.

FIG. 4 is a top and back side perspective view of the drinking cup with a lid of FIG. 1.

FIG. 5 is a bottom and front side perspective view of the drinking cup with a lid of FIG. 1.

FIG. 6 is a top plan view of the drinking cup with a lid of FIG. 1.

FIG. 7 is a bottom plan view of the drinking cup with a lid of FIG. 1.

FIG. 8 is a front elevational view of the drinking cup with a lid of FIG. 1.

FIG. 9 is a right side elevational view of the drinking cup with a lid of FIG. 1.

FIG. 10 is a left side elevational view of the drinking cup with a lid of FIG. 1.

FIG. 11 is a back side elevational view of the drinking cup with a lid of FIG. 1.

FIG. 12 is an exploded, front side perspective view of the drinking cup with a lid of FIG. 1.

FIG. 13 is a cross-sectional view of the drinking cup with a lid along the 13-13 line shown in FIG. 8.

FIG. 14 is a top and front side perspective view of the drinking cup with a lid shown in FIG. 1, with the lid shown separately for ease of illustration.

FIG. 15 is a top and back side perspective view of FIG. 14.

FIG. 16 is a bottom and front side perspective view of FIG. 14.

FIG. 17 is a side elevational view of FIG. 14, the other side elevational views are the same.

(Continued)

FIG. 18 is a top plan view of FIG. 14; and, FIG. 19 is a bottom plan view of FIG. 14. The broken lines depict environment, and the elements shown in broken lines form no part of the claimed design.
